Application October 8, 1936, Serial No. 104,608

3 Claims. (Cl. 28—1)

This invention relates to tapes with corded edges and particularly to a tape which is substantially free from stretching and shrinking effects along the corded edge.

5 One of the difficult problems in the construction of cord edged tapes and particularly zipper tapes has been the prevention of stretching and shrinking and at the same time to produce a rigid and a reasonably pliable material. This tendency toward stretching or shrinking and limberness of 10 fabric is a serious difficulty, especially in zipper tapes, because the metal scoups or other attachments fastened to the corded edge of the tape are thrown out of alignment by unequal stretching or 15 shrinking, and the limberness of the fabric tends to buckle the strips of fasteners and produces unsatisfactory results. As a result the two opposite sides of a zipper fastener, for instance, will not fit perfectly, causing a tearing out of the 20 scoups or a jamming of the fastening element.

Heretofore it has been the practice to wet the finished fastener and then stretch it but this method represents only a temporary solution of the problem because the tapes soon undergo unequal shrinking particularly when washed. It has also been the practice to use substances such as starch and the like in an attempt to solve these difficulties, but these methods also represent only temporary remedies since the starch soon washes 30 out. Substances such as glue are unsuitable because the finished tape must be pliable as well as free from stretching or shrinking effects.

Therefore the principal object of the present invention is to provide a cord edged tape which is substantially free from stretching or shrinking effects particularly in the vicinity of the corded edge.

We have discovered that these difficulties may be obviated by incorporating a number of yarns composed of a cellulose derivative, such as Celanese, which is a cellulose acetate rayon, subjecting the incorporated cellulose derivative to the action of a suitable solvent, and fusing the dissolved cellulose yarn by the application of heat. 40 This results in the production of a stiffening medium which renders the cord and fabric substantially free from stretching or shrinking effects in the vicinity of its formation.

In the drawing, Fig. I shows a perspective view 50 of a fastener comprising two cord edged tapes with scoups attached.

Fig. II is a cross section through II—II of Fig. I, showing one method of constructing a tape according to this invention.

55 Figs. III, IV, and V are cross-sections through

II—II of Fig. I showing different methods of construction.

Figs. VI and VII are cross-sectional views of tapes with sewed-on cords.

With reference to Fig. I, the tapes 1 have corded edges 2 to which are attached scoups 3. A fastening element is shown at 4. The corded edges 2 are made up as shown in Figs. II—VII in which the cord itself is shown at 5 and the cellulose derivative yarns at 6.

10 In Fig. II the cellulose derivative yarns 6 are woven with the cord 5.

In Fig. III the cellulose derivative yarns 6 are incorporated into the cord 5.

15 In Fig. IV a number of separate yarns 7 are shown which are substituted for the twisted cord 5. Cellulose derivative yarns 6 are distributed among the series of yarns 7.

In Fig. V the cellulose derivative yarns 6 are woven into the fabric 1 that covers the cord 5.

20 Fig. VI shows a tape with a sewed-on cord 5 and cellulose derivative threads 6 incorporated in the cord 5.

25 Fig. VII shows a tape with a sewed-on cord 5 and cellulose derivative threads 6 woven into the fabric 1.

30 In carrying out the present invention a cellulose derivative yarn is first incorporated into the tape in some manner similar to those shown in the drawing. A cellulose ester yarn, such as cellulose acetate, has been found especially suitable, but other cellulose derivative yarns may be used. The cellulose derivative yarns are then subjected to the action of a suitable solvent. In the case of cellulose acetate yarns, we have discovered that 35 a solution composed of 3 parts acetone and 1 part methyl alcohol makes a very satisfactory solvent. Other solvents such as acetone alone, or ethyl acetone, may be used, however. Where yarns other than cellulose acetate are used various other suitable solvents may be used. The solvent is applied by either passing the tape through the solvent solution or applying the solvent solution to the tape by wicks, rollers or sprayers. In any event, the solvent treatment is continued for a time sufficient to render the cellulose derivative yarn cementitious. The tape is then placed under tension and subjected to a temperature sufficient to fuse the dissolved cellulose derivative yarn and the surrounding yarns to a pliable but substantially non-stretching, non-shrinking mass. This 45 action, which we have herein referred to as "fusion", produces a tape of the desired qualities by virtue of the fact that the dissolved and heated cellulose yarns permeate the surrounding yarns.

50

and then set in such a way as to cement the yarns into a pliable but non-stretching as well as non-shrinking mass.

5 A tape constructed according to the present invention exhibits many advantages over any tape hitherto available and particularly in the field of zipper tapes. The combination of pliability plus substantial freedom from stretching and shrinking effects prevents the usual troubles arising from mis-alignment of the scoups and adds substantially to the life of the fastener. Moreover it is possible to construct a tape with a perfectly straight edge which will remain straight indefinitely.

10 15 It will be understood that the foregoing description refers to but one preferred embodiment of the present invention and that other cellulose yarns and other solvents may be used coming within the scope of the invention as hereinafter claimed.

20 Having thus described our invention, we claim:

1. A process of producing a tape with an edge that is substantially free from stretching and

shrinking effects, which process comprises incorporating cellulose derivative yarn in the tape fabric, amongst the other yarns composing it, treating the cellulose derivative yarn in the tape fabric with a suitable solvent and thereby rendering the same cementitious; and heating the tape while under tension and thereby fusing the cementitious cellulose derivative material and permeating the surrounding yarns of the fabric therewith, so that when set the cellulose derivative material cements the other yarns into a pliable but non-stretching and non-shrinking condition.

2. A process as set forth in claim 1, wherein the cellulose derivative yarn employed is a cellulose ester yarn.

3. A process as set forth in claim 1, wherein the cellulose derivative yarn employed is a cellulose ester yarn, and the solvent wherewith it is treated comprises acetone and methyl alcohol.
